PRESSER MECHANISMS FOR SEWING MACHINES

Anthony J. Matuzas, Union, N. J., assignor to The Singer Manufacturing Company, Elizabeth, N. J., a corporation of New Jersey

Application October 21, 1955, Serial No. 541,884

10

6 Claims. (Cl. 112—236)

The present invention relates to sewing machine presser mechanisms and has for a primary object to provide a new and improved adjusting means for the presser-bar spring which is acting to depress the presser-foot into contact with the work-supporting surface. It is one of the specific objects of this invention to provide such a means which is of the so-called quick-release type, i. e., it is adapted with a minimum of actuation to vary the presser-depressing pressure between a heavy pressure for normal sewing and light pressure for embroidery or darning.

It is a further object of this invention to provide a new and improved means for varying the pressure of a presser-bar spring, which means includes an actuating element that is mounted for rotation only and which is adapted to cooperate with indicia for indicating the setting of the same and thereby facilitate selection of the proper pressure for the goods being worked.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in the art readily to understand the function, operation, construction and advantages of it when read in conjunction with the accompanying drawings in which:

Fig. 1 is a head end elevational view, partly in section, of a sewing machine embodying the present invention.

Fig. 2 is a fragmentary vertical sectional view taken substantially on the line 2—2 of Fig. 1 illustrating in elevation the presser mechanism of the machine of Fig. 1.

Fig. 3 is a fragmentary top plan view of the machine illustrated in Fig. 1 showing the actuating element of the presser varying means.

Fig. 4 is a horizontal sectional view taken substantially on the line 4—4 of Fig. 2.

Fig. 5 is a fragmentary vertical sectional view similar to Fig. 2 but illustrating the presser mechanism in section.

The presser mechanism as herein illustrated is embodied in a sewing machine having a frame including a work-supporting surface 1 and overhanging head 2. The presser mechanism comprises a presser bar 3 journaled in a sleeve or bushing 4 mounted in said head. At its lower end the presser bar 3 carries a presser-foot 5.

The presser bar 3 is provided with an axial bore 6 extending longitudinally from the upper end thereof, in which bore is disposed a coil compression spring 7. The spring 7 bears at its lower end against the bottom of the bore 6 and thereby acts resiliently to urge the presser bar 3 downwardly with the presser-foot 5 in engagement with the work-supporting surface 1. At its upper end the spring 7 abuts against the lower end of a first or lower rod element 8 which is a part of a two-part rod 9 that also includes a second or upper rod element 10. The rod element 8 extends into an axial bore 11 in a bushing 12 adjustably secured in the upper portion of the head 2 in axial alignment with the presser-bar 3,

2

the bushing 12 having external threads 12a that is threaded into the top of the head and locked by a lock nut 12b. The bushing 12 is provided with an axial displacement cam formation, which cam formation in the illustrated embodiment of the invention comprises a cam surface 13 formed upon the lower end of the bushing. There is provided a cam follower on the rod element 8, which follower comprises a stud 14 fixed to said rod element. With this construction, it will be apparent that the rod element 8 is urged upwardly by the spring 7 to hold the stud 14 in contact with the cam surface 13 which thereby determines the compression of the spring 7 and thus the force urging the presser-foot 5 into contact with the work-supporting surface 1. Upon rotation of the rod element 8 the stud 14 will follow the cam surface 13 of the bushing 12 and the rod element 8 will thereby be displaced axially of the bushing 12 either to compress or to relax the spring 7. The cam surface 13 is designed to move the rod element 8 axially in substantially one revolution from a position of maximum depression, that will effect a relatively heavy spring pressure which is useful for normal sewing, to a position of minimum depression, that will effect a very light pressure on the presser bar, which is useful for embroidery or darning.

Within the bore 11 of the bushing 12, the upper end of rod element 8 and the lower end of the rod element 10 are of circularly complementary cross-section and specifically are slotted to define semi-circular cross-sections Fig. 4. The rod elements 8 and 10 are thus keyed together for unitary rotation though free for axial sliding relative to one another. At its upper end, the rod element 10 is reduced to form a shoulder 15 and a reduced portion 16. The upper end of bore 11 in the bushing 12 is also reduced in diameter to form a shoulder 17. The end portion 16 of the rod element 10 extends through the reduced diameter portion of the bore 11 and extends from the bushing to the exterior of the head 2. Upon the portion 16 extending from the head is secured a knob or finger-piece 18 as by a set screw 19. When assembled, the shoulder 15 and the knob 18 hold the rod element 10 against axial sliding movement in the bushing 12. The rod element 10 is free to be rotated and when rotated it will impart rotation to the rod element 8. As explained above, rotation of the rod element 8 will, by virtue of the cam follower stud 14 and cam formation 13, impart axial sliding movement to the rod element 8, and consequently will vary the compression of the spring 7.

As best seen in Fig. 3, the knob 18 is provided with indicia 20 that is designed to cooperate with an indicator mark 21 to indicate the setting of the same, and thus indicate the compression of the spring 7 and the pressure with which it is urging the presser bar into engagement with the work-supporting surface 1. The knob 18 is restrained against accidental rotation by means of a yieldable detent-pin 22 seated in a hole 23 in the knob 18 and extending upwardly into the knob 18 from the bottom face thereof. The detent-pin 22 is biased downwardly by a spring 24, the ball-shaped lower end 25 of the detent-pin cooperating with a series of notches 26 about the upper face of the bushing 12.

Numerous alterations of the structure herein disclosed will suggest themselves to those skilled in the art. However, it is to be understood that the present disclosure relates to a preferred embodiment of my invention which is for purposes of illustration only and not to be construed as a limitation of the invention. All such modifications which do not depart from the spirit of the invention are intended to be included within the scope of the appended claims.

Having thus described the nature of the invention, what I claim herein is:

1. An adjustable presser mechanism for a sewing machine having a frame, said presser mechanism comprising a presser bar mounted in said frame for longitudinal sliding movements, a coil compression spring arranged coaxially of and operatively connected to said presser bar for biasing the same for axial sliding movement, and an adjustable abutment for said spring for varying the compression thereof, said adjustable abutment comprising a bushing secured in said frame, a cam surface formed upon the end of said bushing adjacent said presser bar, a two-part rod journaled for rotation in said bushing, said rod having a first rod element and a second rod element axially slidable relative to one another but keyed together for unitary rotation, said first element forming an abutment for said spring and said second element extending from said bushing to the exterior of said frame whereby it may be manually grasped for rotating the same, means for confining said second element against axial movement, a cam follower carried by said first element and cooperating with said cam surface on said bushing for sliding said first element axially upon rotation thereof and thereby varying the compression of said spring.

2. An adjustable presser mechanism for a sewing machine having a frame, said presser mechanism comprising a presser bar mounted in said frame for longitudinal sliding movements and having an axial bore extending inwardly from one end thereof, a coil compression spring disposed within said bore and abutting at one end against the bottom of said bore, and an adjustable abutment for the other end of said spring for varying the compression thereof, said adjustable abutment comprising a bushing secured in said frame, a cam surface formed upon the end of said bushing adjacent said presser bar, a two-part rod journaled in said bushing, said rod having a first rod element and a second rod element axially slidable relative to one another but keyed together for unitary rotation, said first element extending into the bore in said presser bar and said second element extending from said bushing to the exterior of said frame whereby it may be manually grasped for rotating the same, means for confining said second element against axial movement, a cam follower carried by said first element and cooperating with cam surface on said bushing for sliding said first element axially upon rotation thereof and thereby varying the compression of said spring, and indicia carried by said second element to indicate the setting thereof and thus indicate the compression of the spring.

3. An adjustable presser mechanism for a sewing machine having a frame, said presser mechanism comprising a presser bar mounted in said frame for longitudinal sliding movements, spring means operatively connected to said presser bar for biasing the same for axial sliding movement, and adjustable means operatively connected to said spring for varying the resilient action thereof, said adjustable means comprising a two-part rod journaled for rotation in said frame, said rod having a first rod element and a second rod element axially slidable relative to one another but keyed together for unitary rotation, said first element abutting against said spring for varying the resilient action thereof upon axial movement of said first element, said second element comprising an actuating member whereby said rod may be rotated, means for confining said second element against axial movement, and means associated with said first element for imparting axial movement thereto upon rotation of said first rod element.

4. An adjustable presser mechanism for a sewing machine having a frame, said presser mechanism comprising a presser bar mounted in said frame for longitudinal sliding movements, a coil compression spring arranged coaxially of and operatively connected to said presser bar for biasing the same for axial sliding movement, and an adjustable abutment for said spring for varying the compression thereof, said adjustable abutment comprising a bushing secured in said frame and a two-part rod journaled for rotation in said bushing, said rod having a first rod element and a second rod element axially slidable relative to one another but keyed together for unitary rotation, said first element abutting against said spring for varying the compression thereof upon axial movement of said first element, said second element extending through said bushing and comprising an actuating member whereby said rod may be rotated, means for confining said second element against axial movement, and means associated with said first element for imparting axial movement thereto upon rotation thereof.

5. A quick-release device for the presser mechanism of a sewing machine comprising an externally threaded bushing adapted to be screwed into the head of a sewing machine and having a bore, an axial displacement cam on said bushing, a two part rod journaled in said bushing, said rod having a first rod element and a second rod element axially slidable relative to one another but keyed together for unitary rotation, said first rod element extending from the lower end of said bushing, said second rod element extending from the upper end of said bushing, means upon the exposed end of said second rod element to provide for manually rotating the same, means for confining said second rod element against axial movement, a cam follower carried by said first rod element and cooperating with said axial displacement cam for sliding said first rod element axially upon rotation thereof.

6. An adjustable presser mechanism for a sewing machine having a frame, said presser mechanism comprising a presser bar mounted in said frame for axial sliding movements, spring means operatively connected to said presser bar for biasing the same for axial sliding movements, and an adjustable abutment mounted in said frame and operatively connected to said spring for varying the resilient action thereof, said adjustable abutment including a pair of elements comprising a bushing having a bore and a rod mounted in the bore of said bushing for axial sliding movement, one end of said rod forming an abutment for said spring, an axial displacement cam formation upon one of said elements and a cooperating cam follower upon the other of said elements for sliding said rod axially upon relative rotation between said rod and bushing, an actuating member, means mounting said actuating member in said frame for rotation and for holding the same against endwise movement relative to said frame, and means operatively connecting said actuating member to one of said elements for unitary rotation and for relative movement endwise for effecting relative rotation between said rod and bushing upon rotation of said actuating member and thereby sliding said rod axially and varying the resilient action of said spring.
